UNITED STATES PATENT OFFICE.

GUSTAV B. REISBACH, OF MILWAUKEE, WISCONSIN, ASSIGNOR TO THE CUTLER HAMMER MFG. CO., OF MILWAUKEE, WISCONSIN, A CORPORATION OF WISCONSIN.

RHEOSTAT.

1,137,352.

Specification of Letters Patent.

Patented Apr. 27, 1915.

Application filed May 8, 1914. Serial No. 836,744.

To all whom it may concern:

Be it known that I, GUSTAV B. REISBACH, a citizen of the United States, residing at Milwaukee, in the county of Milwaukee and State of Wisconsin, have invented new and useful Improvements in Rheostats, of which the following is a full, clear, concise, and exact description, reference being had to the accompanying drawing, forming a part of this specification.

This invention relates to rheostats and more particularly to clamping means for the control levers thereof. One of the objects of the invention is to provide means to enable independent adjustment of a plurality of levers on a common shaft and simultaneous operation thereof when adjusted in any relative position.

In the accompanying drawing, showing a preferred embodiment of the invention as applied to a theater dimmer, Figure 1 is a side view of a dimmer unit showing in section a clamping device for the control lever; and, Fig. 2 is a front view thereof, showing two additional dimmer units arranged in bank formation.

Each dimmer unit comprises a rheostat plate 1 having a pivoted arm 2 arranged to sweep over a series of contacts 3 connected to the resistance carried by the plate 1. The arm 2 is provided with a central pinion 4 meshing with a rack 5 connected to a control lever 6 rotatable on a shaft 7. The rack 5 is held in engagement with the pinion 4 by a pivoted yoke 8 which permits variation of the tangent angle of the rack when reciprocated by movement of the lever 6.

A plurality of the rheostats are preferably mounted side by side with the operating levers 6 of each arranged on the common master shaft 7 and normally capable of independent movement thereon. It is frequently desirable, however, to operate a number of dimmers, or the entire bank thereof, simultaneously through the medium of a master lever 9 fixed to turn the shaft 7.

Each lever 6 comprises a bracket 10 having bearings on the shaft 7 and inclosing a split ring or collar 11 which encircles the shaft. The two ends of the ring 11 are biased slightly apart but are restrained against separation between a bracket shoulder 12 and the end of a spindle 13 threaded through a second bracket shoulder 14. The free end of the spindle 13 is connected to

the handle 15 of the lever 6 whereby rotation of the handle raises or lowers the spindle to expand or contract the ring 11. Each of the levers 6 may thus be independently adjusted to any angle and clamped to the shaft 7 by turning the spindle 13 so that the ring 11 grips the shaft 7 and locks the operating lever in definite relation therewith. Accordingly, the arms 2 of the separate rheostats may be set at any desired positions and simultaneously actuated by the master lever 9 irrespective of such initial position and without disturbing the relative angles of the separate levers 6.

What I claim as new and desire to secure by Letters Patent is:

1. The combination with a plurality of rheostats, of an operating member for each, a common supporting shaft for said members, means associated with each of said members to fix the same to said shaft in any angular position relative thereto, and a master lever for turning said shaft to operate all of said levers simultaneously.

2. The combination with a plurality of rheostats having movable contact arms, of a shaft, an independently operable lever for each of said arms loosely fulcrumed on said shaft, an operative connection between each of said levers and its respective arm, means associated with each of said levers to clamp the same to said shaft in the position thereof corresponding to any adjustment of its respective arm, and a master lever for turning said shaft.

3. The combination with a plurality of rheostats, of a pivoted operating lever for each, a common supporting shaft on which all of said levers are loosely fulcrumed, a master lever for turning said shaft, and operative connecting means between said shaft and each of said pivoted levers for fixing the latter to the former in any angular position relative thereto, said means comprising a compressible collar loosely encircling said shaft and a threaded spindle carried by said lever and rotatable for tightening said collar to said shaft.

4. The combination with a plurality of rheostats having movable contact arms, of a pivoted operating lever for each of said arms, a common supporting shaft on which all of said levers are loosely fulcrumed, a member having a fixed relation with each of said levers and relatively movable with

respect to said shaft, means carried by each of said levers for rendering its respective member fixed to said shaft in any angular position of the lever, said levers being independently operable and said means being independently operable, and a master lever for rotating said shaft.

In witness whereof, I have hereunto subscribed my name in the presence of two witnesses.

GUSTAV B. REISBACH.
